CLAIM

The ornamental design for a surgical tool cam handle, as shown and described.

DESCRIPTION

FIG. 1 is a perspective view of a surgical tool cam handle in accordance with my new design;

FIG. 2 is a right side view of the surgical tool cam handle of FIG. 1;

FIG. 3 is a left side view of the surgical tool cam handle of FIG. 1;

FIG. 4 is a top view of the surgical tool cam handle of FIG. 1;

FIG. 5 is a bottom view of the surgical tool cam handle of FIG. 1;

FIG. 6 is a front view of the surgical tool cam handle of FIG. 1; and,

FIG. 7 is a rear view of the surgical tool cam handle of FIG. 1;

In the drawings, the broken lines illustrate portions of the surgical tool cam handle that form no part of the claimed design.

1 Claim, 6 Drawing Sheets
